UNITED STATES PATENT OFFICE.

CHARLES S. RICE, JR., OF CHICAGO, ILLINOIS.

DISINFECTION APPARATUS FOR WATER-CLOSETS.

SPECIFICATION forming part of Letters Patent No. 276,470, dated April 24, 1883.

Application filed November 8, 1882. (No model.)

To all whom it may concern:

Be it known that I, CHARLES S. RICE, Jr., a citizen of the United States of America, residing at Chicago, in the county of Cook and State of Illinois, have invented an Improvement in Disinfecting Apparatus for Water-Closets, of which the following is a specification, to wit:

This invention relates to devices for disinfecting water-closets or similar places; and it consists in the construction and arrangement of parts, as hereinafter more fully described and claimed.

In order to enable others skilled in the art to which my invention appertains to make and use the same, I will now proceed to describe its construction and operation, referring to the accompanying drawings, in which—

Figure 1 is a front view of my invention as arranged for use. Fig. 2 is a similar view enlarged, with the front of the case removed; and Fig. 3 is a vertical cross-section of the operating devices of the invention.

A represents a box or case, which is divided into two compartments, the upper one of which is provided with a small vessel, B, having a bellows, B', communicating with it, as shown. The upper side of this bellows is weighted, as seen at a a, and is attached to a cord or chain, b, passing over a series of pulleys, b', and out through an opening, a', in the front of the case A. The vessel B is filled with a disinfecting-liquid—such, for instance, as thymol—and is furnished with a small pipe or tube, c, which communicates with the outer air through a grated opening, c', in the front of the case, as seen in Fig. 1.

When the article is placed in a water-closet, the cord or chain b is attached to the hinged lid over the bowl, and when this is shut the bellows is expanded and air drawn into the vessel B through the pipe c, where it becomes impregnated with the vapor of the disinfectant. When the lid is raised to use the closet the bellows is released, and, being forced down by the weights a a, drives out the air charged with disinfectant, which spreads itself through the closet, thoroughly destroying any germs of disease which may be floating in the air, without leaving behind any unpleasant smell.

In the lower compartment of the case or box A is a box, C, which is provided with an open-

ing, d, in its upper end, sealed by a cover, C', which is held in position upon a rubber packing-cushion, C², by means of a thumb-screw, d', working through a small frame, d², upon the box or receptacle C. The upper end of the box C is connected with a water-pipe, D, which leads to a reservoir or communicates with the street-mains, and is provided with a stop-cock, D', to regulate the flow.

E is the escape-pipe, which passes through the bottom of the box C and rises nearly to its upper end, as seen by Fig. 3. This box is filled with a powdered disinfectant—such as chloride of zinc—nearly to the top of the escape-pipe, which latter is at its opposite end connected to the closet-bowl. The stop-cock D' is then turned to allow a constant drip of water into the receptacle C, which soon accumulates, dissolves a portion of the chloride of zinc, and constantly overflows through the pipe E to the bowl, thereby not only destroying the germs in any deposits, but also in any gas which may be forced back into the closet when not in use.

This device does not in any way interfere with the flushing of the bowl or mar its easings. In such devices as ordinarily constructed with open vessels for containing the powdered disinfectant, the sediment sometimes stops up the escape-pipe and causes the water to overflow; but in the present invention the receptacle, being sealed securely, is not liable to such overflow, and should the pipe E become obstructed the pressure of the water would eventually force it clear.

To prevent noise of the dripping water when the disinfectant has been partly used, and also to cause such drip to descend to the bottom, I provide a short section of pipe, E', placed directly under the inlet-pipe D, and extending down some distance into the chloride of zinc, as shown by Fig. 3, which guides the drip and aids in loosening the particles of zinc from the general mass.

Having thus fully described my invention, what I claim as new, and desire to secure by Letters Patent, is—

1. In a disinfecting apparatus for water-closets and the like, the combination, with a vessel for containing liquid disinfectant, and having a single air inlet and outlet, of a weighted bellows and means for expanding the same,

whereby air is drawn into and forced out of said vessel through a single pipe, substantially as shown and described.

2. In a disinfecting apparatus for water closets, the combination, with the vessel C, having a supply-pipe, D, and escape-pipe E, arranged substantially as described, of the short section of pipe E', located directly un-

der the supply-pipe, as and for the purpose herein described.

In testimony whereof I affix my signature in presence of two witnesses.

CHARLES S. RICE, JR.
